CLAIM

The ornamental design for an electrically driven pump, as shown and described.

DESCRIPTION

FIG. 1 is a front view of an electrically driven pump according to the present application;

FIG. 2 is a rear view of the electrically driven pump according to the first embodiment of the present application;

FIG. 3 is a left view of the electrically driven pump according to the first embodiment of the present application;

FIG. 4 is a right view of the electrically driven pump according to the first embodiment of the present application;

FIG. 5 is a top view of the electrically driven pump according to the first embodiment of the present application;

FIG. 6 is a bottom view of the electrically driven pump according to the first embodiment of the present application; and,

FIG. 7 is a perspective view of the electrically driven pump according to the first embodiment of the present application.

The broken lines shown in the figures are portions of the electrically driven pump that form no part of the claimed design.
